PANTOGRAPH

Erik Walter Derwén and Kay Herbert Honkanen,
Stockholm, SwedenApplication July 3, 1950, Serial No. 171,990
In Sweden February 24, 1949

4 Claims. (Cl. 33—23)

1

The present invention relates to pantographs and has for its object to provide an improved pantograph capable of adjustment to determine the inclination and/or size of the reproduction relative to the letters or pattern of the stencil.

The invention is primarily distinguished by the feature that a pivoted arm system arranged on a base plate is composed, first, of a principal arm, one end of which is guided along a rod or other guiding means secured on the base plate, second, of a guide arm pivoted to the other end of the principal arm and adapted to be secured in various angular positions, said guide arm being provided with a tracing pin or the like adapted to be moved on a stencil having marks thereon corresponding to the symbols and so forth to be rendered, and, third, of a writing arm with a writing style, said writing arm being displaceable along the principal arm and adapted to be secured in different positions along the same. With the use of one and the same stencil said contrivance makes it possible by simple adjustments, that is to say, by adjusting and locking the guide arm in different angular positions on the principal arm, to obtain the desired inclination of the letters of the text matter to be rendered relatively to the text matter on the stencil. In addition, an enlargement or reduction of the text matter is rendered possible in accordance with the adjustments of the writing arm into different positions along the principal arm.

Further features of the invention and advantages derived therefrom will appear from the following description of a form of embodiment illustrated in the accompanying drawings in which:

Fig. 1 is a plan view of the pantograph, the left hand portion of the base being broken away to shorten the figure;

Fig. 2 is a front elevation of the pantograph with the left hand end of the base broken away;

Fig. 3 is a detached view showing the connection of the main arm to the guide rail;

Fig. 4 is a section on the line 4—4 of Fig. 1;

Fig. 5 is a section on the line 5—5 of Fig. 1;

Fig. 6 is a perspective view of the writing style;

Fig. 7 is a plan view of the end portion of the principal arm and guide arm;

Fig. 8 is a plan view of a modified form of base, and

Fig. 9 is a section on the line 9—9 of Fig. 8.

Referring to Figs. 1—7, the base plate is in two parts 1 and 1', adjustably connected in spaced parallel relationship by rails 23 which lie in the grooves 22 in the lower side of the base plate,

2

being fixedly secured to the part 1' by the rivets 24 and adjustably secured to the part 1 by the screws 25. Only one rail 23 is shown but it will be understood that another similar rail is associated with the broken away portion of the base plate. Turning the screws 25 moves the part 1 relative to the part 1' and determines the width of the space between them.

Part 1 of the base plate carries the rod 2 and part 1' carries the stencil 3. The principal arm 5 is pivotally and slidably connected at its right hand end to the transverse arm 6 by means of the clamping screw 17 which extends through a circular opening in the arm 5 and through the slot 36 in the arm 6. Transverse arm 6 is connected by the rivet 7 to the guide spring 7 which is slidable along the rod 2. Spring 7 with the attached arms 5, 6, 8 and 13 readily may be detached from the rod 2. The principal arm 5 carries the guide arm 13 and tracing pin 14, arm 13 being adjustably pivotally attached to the left hand end of the arm 5 by means of the clamping screw 15. The arm 5 carries also the writing arm 8 with its writing style 11. Writing arm 8 is slidably attached to arm 5 by means of the runner 9 and the clamping screw 18.

The writing style 11 is secured to the end of the arm 8 by the band spring 16 having laterally projecting channel shaped ends 10, 10 which fit into a vertical slot 10' in the end of the arm 8 and over the upper and lower edges thereof. Thus the spring 16 is readily detachable from the arm 8 for exchanging the writing style. The style 11 is slidably adjustable up and down in the spring 16. Arm 8 carries the spacing member 12 which determines the spacing between the letters or symbols being made.

Text matter reduced or enlarged relatively to the text matter of the stencil may be obtained by the runner 9 being displaced toward and away from the connection of the principal arm 5 with the guide spring 7. The principal arm may be provided with a scale from which the position of the runner may be read off.

The guide arm 13 may be provided with an index and the principal arm with corresponding scale lines, whereby the angle between these arms is indicated.

The whole of the apparatus may be displaceably guided along a lateral guide taking the form of a rod 29, to which part 1 of the base plate is connected by means of a connecting strap 27 and a tension screw 28. A graduated ruler 20, which is preferably transparent and facilitates reading of the line spacing and the marginal

width, may be connected by means of a slide spring 19 to the rod 2 arranged on the base plate.

The stencil or stencils 3 may be retained in their place on the base plate by means of an upwardly projecting edge fillet 21 on the part 1' of the base plate as well as by means of a tension spring 4, which is secured to the part 1 of the base plate and projects inwardly over the stencil in a groove extending in the longitudinal direction of the stencil, as appears from Figs. 1 and 4.

The symbols of the stencil, such as letters, figures, or the like, are made in the form of depressions in the stencil. In the use of the apparatus, the pin 14 is moved along these depressions, the principal arm being thus displaced by the fact that the slide spring 7 is caused to slide along the rod 2, whereat the principal arm is also turned about the rivet 7' connecting the spring 7 and the transverse arm 6. If the writing style 11 then bears on a work sheet, the style is caused to write the corresponding symbol thereon. If the arm 13 is then adjusted to form an extension of the principal arm 5, as shown by full lines in Fig. 7, a relatively upright lettering will be obtained. On the other hand, if the arm 13 is adjusted to form an angle with the principal arm, as shown by dash lines in Fig. 7, the lettering will slope more forwardly, provided the lettering of the stencil is upright. By adjusting the arm 13 to different angular positions relatively to the principal arm, it will thus be possible to obtain varying inclinations of the lettering. An enlargement or reduction may be obtained, as stated, by adjusting the runner 9 into different positions along the principal arm, counted in the longitudinal direction of the latter.

In the modified construction according to Figs. 8 and 9, the one member 1b of the two members of the base plate is arranged as a bed for the other member 1a so as to carry both the latter and the stencil. The member 1a is displaceably guided on the member 1b by means of screws 30 extending through transverse slits 31 in the base plate member 1b while also extending freely through apertures in the member 1a, where the screws are retained by means of nuts 32. The base plate 1b may be made from sheet-metal, and is provided with upwardly projecting lateral edges 33, 34. A stencil 35 placed upon the base plate 1b is retained in position by being moved against the upwardly turned lateral edge 34, and is caused to bear against the latter with the aid of the member 1a which, guided by the screws 30 and the slits 31, may be moved to bear on the opposite edge of the stencil. The member 1a may be locked in this operative position with the end of the nuts 32 and the screws 30.

The form of embodiment shown may be modification by arranging the slits in the member 1a and the screws in apertures provided in the base member 1b.

What we claim is:

1. A pantograph comprising a base consisting of two parts having adjacent, straight parallel edges, means securing said two parts together with said parallel edges at adjustable distances from each other, a rod secured to one of said

parts and extending parallel to said parallel edges, a first arm having one end pivotally and slidably connected to said rod, a second arm having one end pivotally and slidably connected to said first arm, means for securing said second arm in adjusted position with respect to said first arm, a third arm having one end pivotally connected to the other end of said second arm, means for securing said third arm in adjusted position with respect to said second arm, a tracing pin carried by the free end of said third arm, a fourth arm having one end slidably connected to said second arm, means for securing said fourth arm in adjusted position with respect to said second arm, a writing style carried by the other end of said fourth arm, means on said base for slidably supporting a stencil, and means on said base for retaining said stencil in adjusted position with respect to said base.

2. A pantograph as defined in claim 1 in which the rod is secured to one of the parts of the base and the stencil is supported on the other part of said base.

3. A pantograph as defined in claim 1 in which one part of said base consists of a flat plate having upwardly projecting walls on opposite parallel edges thereof and the other part of the base is supported on said plate.

4. A pantograph comprising a base consisting of two parts having adjacent, straight parallel edges, means securing said two parts together with said parallel edges at adjustable distances from each other, a rod secured to one of said parts and extending parallel to said parallel edges, a first arm having one end pivotally and slidably connected to said rod, a second arm having one end pivotally connected to the other end of said first arm, means for securing said second arm in adjusted position with respect to said first arm, a tracing pin carried by the free end of said second arm, a third arm having one end slidably connected to said first arm, means for securing said third arm in adjusted position with respect to said first arm, a writing style carried by the other end of said third arm, means on said base for slidably supporting a stencil, and means on said base for retaining said stencil in adjusted position with respect to said base.
